CONTAINER CLOSURE

Benno Cohn, Brooklyn, N. Y., assignor to Ferdinand Gutmann & Co., Brooklyn, N. Y., a corporation of New York

Application July 3, 1933, Serial No. 678,843

6 Claims. (Cl. 215—43)

The invention relates to container closures, and more particularly to a closure of the re-seal type in which the skirt is provided with screw threads or other means adapted to co-operate with complementary means upon the neck of a bottle or container to facilitate the attachment and removal of the closure and cause the necessary compression of a sealing disk or gasket to form an effective seal about the top of the container neck.

5 Prior to my invention, it has been a common practice to produce such closures or caps having a drawn metal shell, the skirt of which had formed therein the screw threads or other attaching means. In such closures or caps the 10 lower edge of the skirt was rolled outwardly to form a stiffening bead and also give a finish to the bottom of the skirt and avoid the presence of a sharp edge.

It has also been the practice to provide such a 15 closure or cap with a drawn metal outer shell conforming to, inclosing and secured to the usual cap structure.

In the co-pending application of Jesse Gutmann, Serial No. 595,001, there is disclosed a 20 closure or cap having a non-metallic tubular member made of bakelite or other material inclosed by a drawn metal shell, the sealing disk or gasket being positioned between one end of the tubular element and the top of the metal shell. 25 This construction of cap is highly effective particularly in the packaging of materials which might be deleteriously affected in the event of contact with a shell having a metal skirt.

This construction of closure or cap is more expensive to produce than the ordinary re-seal 30 closure or cap and has a field of use limited to the packaging of special materials. The rigidity of the tubular element in this type of closure has the advantage that there is no likelihood of such 35 a deformation of the attaching members as will interfere with a proper application of the closure or cap to a container by machines used for this purpose.

With the above conditions in mind, I have provided a container closure or cap having a bi-part 40 all metal shell, the inner tubular element of which is provided with means by which the closure or cap may be attached to a container neck and the outer element of which presents a smooth exterior surface throughout so as to permit it to be decorated in a manner to give an attractive finish to the closure or cap or have applied thereto matter indicating the origin of the contents of a container.

45 The inner tubular element is so formed as to

assure an accurate centering thereof in relation to the outer element or shell proper and a stiffening not only of the tubular element, itself, but of the outer shell.

The outer shell prevents elongation or other 5 deformation of the inner tubular element and serves as a protection for the edges thereof. Furthermore, the stiffening means at the end of the tubular element adjacent the top of the outer shell forms an effective seat for a sealing disk or 10 gasket, between which seat and the top of the shell during the assembling operation, the gasket may be compressed to avoid likelihood of the seepage of the fluid contents of a container between the top of the metal shell and the reinforcing flange of the tubular element, into the space 15 between the two elements.

In a closure or cap embodying the invention, it is possible to use thin gauge metal in the tubular element which may be of harder metal stock 20 than the outer shell, if desired, because of the facility with which thinner stock can be worked.

The construction and arrangement of the two parts of the shell are such that during the assembling operation, sufficient friction will be developed between the stiffening flanges of the tubular element and the skirt of the outer shell to ensure a desired permanency in the relation of these parts to permit the turning of the closure or cap as a whole, by the capping machine, the 25 top reinforcement of the tubular element preventing distortion of the skirted shell during the applying operation by the machine.

The invention consists primarily in a container closure embodying therein an inner tubular metallic element open at both ends, and having adjacent each end thereof an outwardly directed reinforcing flange and attaching means intermediate said flanges, an outer element, having a top closing one end of the tubular element, and a 30 skirt spaced from said attaching means with its lower edge formed about the opposite end of said tubular element, and a packing gasket or disk adjacent the top of the outer element; and in such other novel features of construction and combination of parts as are hereinafter set forth and described, and more particularly pointed out in the 35 claims hereto appended.

Referring to the drawing:

Fig. 1 is a side view of a container closure embodying the invention partly in section, the neck of a bottle being shown in relation thereto, in dotted lines;

Fig. 2 is a sectional view of the inner tubular 45

element prior to its assembly in the completed closure or cap;

Fig. 3 is a sectional view of the outer element prior to its assembly in the completed cap;

5 Fig. 4 is a view of a modified form of the invention in which the top of the outer element is normally "domed"; and

Fig. 5 is a fragmentary portion of the sealing gasket and supplemental top shown in Fig. 4 10 with a portion of the stem of an applicator connected therewith.

Like numerals refer to like parts throughout the several views.

In the embodiment of the invention shown in 15 the drawing, the inner tubular element 10 is provided with screw threads 11 intermediate the ends thereof. At the top of the element is formed an outwardly directed flange 12, the edge of which is curved downward slightly to facilitate the fitting 20 of the inner element in the outer element during the assembly of the closure or cap. At the opposite end of the bottom of this tubular inner element is an outwardly directed flange 13 having a downwardly presented curved portion adjacent 25 its outer edge to facilitate the forming of the lower edge of the skirt of the outer element about this edge and further to form a shoulder 14 against which the edge of the skirt may be formed so as to bring said formed edge outside 30 the inner plane of the tubular element and also conceal the rough edge of the skirt.

The inner tubular element whether it be made of sheet metal formed about a mandrel, or of a tube, may be made of fairly thin gauge metal. 35 When made of sheet metal, no seaming of the abutting edges is required, since the mounting of the inner element in the skirted outer element will bring these edges into abutting relation to each other and hold them in this relation.

40 The outer cap element consists of a drawn metal shell having a top 15 extending across the open top of the tubular element 10 and a skirt 16, the inner form of which engages the edges of the stiffening flanges 12 and 13, the portion 17 45 of the lower edge of this skirt being formed below the lower flange 13 and conformed to the curved portion thereof as described.

The maximum diameter of the inner element 10 is such as to cause the flanges 12 and 13 to 50 have a close sliding fit within the skirt 16 of the outer element, and during the assembling operation, the skirt will be drawn inwardly of the closure or cap sufficiently to develop the desired frictional contact or bite between the skirt and 55 the edges of said flanges.

Preferably, the outer element has a smooth exterior finish throughout, any decorations or other matter being lithographed on the metal sheets of which this element is made, in a manner well known in the production of container closures.

In the completed product, the inner and outer elements of the shell form a composite shell, the parts of which are so firmly and rigidly connected, notwithstanding that they are produced one entirely independently of the other, as to permit the turning of the composite shell as a unit. If desired, the lower flange 13 and the portion 17 of the skirt may be bonded together 70 by an adhesive. This, however, is not essential.

The outwardly directed top flange 12 may be utilized as a seat for a sealing disk or gasket 18 which may be of natural or composition cork or any other of the various materials commonly used 75 in re-seal closures. This disk or gasket is po-

sitioned between the said flange 12 and the top 15 of the outer shell and the portion adjacent the edge thereof is preferably firmly compressed between said flange and said top, in a manner to form an effective barrier against possible seepage of liquid about said flange to the space between the two elements of the composite metal shell.

It will be noted that with the construction heretofore described, a free flexure of the top 15 of the outer element, as a result of the application of compressive stresses to the gasket 18, is permitted. This is a desideratum, in a closure, since the top of a shell when so flexed has a constant tendency to resume its normal flat position thus developing a continuing top pressure upon the gasket throughout the area of its contact with the top of the neck of a container.

15 In the embodiment of the invention shown in Fig. 4, the outer element is formed with an upwardly dished top as indicated at 19, there being positioned between this top and the cushion disk 18, a supplemental metal disk top 20 functioning in the same manner, as the top 15 in the form of the invention shown in Fig. 1, in developing continuing stresses after the application of the closure to a container. In other respects, the construction shown in said figure is the same as in Fig. 1, and the same reference numerals are applied to the corresponding parts.

20 When using a "domed" top for the shell, as shown in Fig. 4, space is afforded above the supplemental top 20 for the accommodation of the upset end 21 of an applicator rod 22 as shown in Fig. 5.

25 At 23, I have shown, in dotted lines, a fragmentary portion of the neck of a container provided with means consisting of screw threads 24 adapted to be engaged by the screw threads 11 of the inner tubular element 10.

30 While I have shown and referred to the use of screw threads as the means for attaching the closure to a container, it will be understood that any other well known form of attaching means may be used so long as the formation thereof is such as to draw the closure downwardly and cause the desired compression of the sealing disk or gasket 18 with the turning of the closure.

35 By the construction of composite shell herein described, it is possible to provide a skirt, the depth of which will be uniform as to all closures irrespective of variance of the thickness of different sealing disks or gaskets so as to avoid possibility of the failure to form a proper seal about the neck of a container by reason of the engagement of the lower edge of the skirt with the head 25 about the neck of a bottle.

40 Furthermore, any possibility of such deformation of the inner tubular element as will interfere with the accurate fitting to the attaching means 24, is impossible since the outside of the tubular element 10 is protected by the skirt 16 from contact with mechanisms of the cap applying machine and this tubular element is firmly held between the formed portion 14 of the skirt 16 and the gasket 18.

45 In the event of irregularities of the attachment means 24, the co-operating attachment means 11 upon the tubular element will conform thereto, particularly as intermediate the flanges 12 and 13 said tubular element may flex outwardly slightly by reason of the space between same and the skirt 16. Such flexure will never be material, but it is desirable to give a certain degree of flexibility to the tubular element, so 50

that it will readily accommodate itself to the co-operating attaching means.

When attaching the closure to a container, vertical stresses are applied to the outer shell 5 by the downward movement of the inner element through the formed lower edge thereof, the compressive stresses applied to the sealing disk or gasket being developed as a result of this downward movement. The skirt 14 being perfectly 10 smooth, there is no possibility of elongation of the tubular element even though it be made of fairly thin gauge metal stock. By making the inner element and the outer element of two 15 separate parts, it is possible to form each of these parts with great accuracy by means of special tools, and yet secure a rigid composite structure. It is possible to assemble the sealing disk or gasket within the shell in the manner described although this is not essential to the invention. 20 It will be noted that the flange 12 notwithstanding the spacing of the wall of the inner element and the wall of the outer element will resist any crushing stresses by the head of the applying machine upon the shell by reason of 25 the location of this flange.

The cushion disk 18, if it be mounted in the shell in the manner herein described, will assist in firmly securing the two elements of the bi-part shell in relation to each other.

30 It is not my intention to limit the invention to the precise details of construction and combination of parts, it being apparent that such may be varied without departing from the spirit and scope of the invention.

35 Having described the invention, what I claim as new and desire to have protected by Letters Patent, is:—

1. A container closure embodying therein an inner tubular metallic element open at both ends 40 and having adjacent each end thereof, an outwardly directed reinforcing flange and attaching means intermediate said flanges, an outer element, having a top closing one end of the tubular element, and a skirt spaced from said 45 attaching means with its lower edge formed about the opposite end of said tubular element, and a packing gasket or disk adjacent the top of the outer element.

2. A container closure embodying therein an 50 inner tubular metallic element open at both ends and having adjacent each end thereof, an outwardly directed reinforcing flange and attaching means intermediate said flanges, an outer element, having a top closing one end of the tubular element, and a skirt spaced from said

attaching means with its lower edge formed about the opposite end of said tubular element, and a packing gasket or disk positioned between one of the end flanges of said inner tubular element and the top of the outer element. 5

3. A container closure embodying therein an inner tubular metallic element open at both ends, an integral outwardly directed top flange, an outwardly directed bottom flange and attaching means intermediate said flanges, said bottom 10 flange having a downwardly curved portion forming a shoulder outside of the inner face of said inner element, an outer element having a top closing one end of the tubular element, and a skirt spaced from said attaching means with its 15 lower edge formed about the curved portion of said flange and against said shoulder, and a packing gasket or disk adjacent the top of the outer element.

4. A container closure embodying therein an 20 inner tubular metallic element open at both ends and having adjacent each end thereof an outwardly directed reinforcing flange, and attaching means intermediate said flanges, an outer element having a top closing one end of the 25 tubular element, and a skirt engaging the edge of both of said flanges and having its lower edge formed about the opposite end of said tubular element, and a packing gasket or disk adjacent the top of the outer element. 30

5. A container closure embodying therein an inner tubular element formed of sheet metal open at both ends and having adjacent each end thereof, an outwardly directed reinforcing flange and attaching means intermediate said flanges, 35 an outer element, having a top closing one end of the tubular element, and a skirt spaced from said attaching means with its lower edge formed about the opposite end of said tubular element, and a packing gasket or disk adjacent the top 40 of the outer element.

6. A container closure embodying therein an inner tubular element formed of sheet metal open at both ends and having adjacent each end thereof, an outwardly directed reinforcing flange 45 and attaching means intermediate said flanges, an outer element, having a top closing one end of the tubular element, and a skirt spaced from said attaching means with its lower edge formed about the opposite end of said tubular element, 50 and a packing gasket or disk positioned between one of the end flanges of said inner tubular element and the top of the outer element.
